UNITED STATES PATENT OFFICE.

WILLIAM ROBINSON, OF BROOKLYN, NEW YORK.

ADJUSTABLE PLATFORM FOR RAILWAY-CARS.

No. 910,383.

Specification of Letters Patent. Patented April 27, 1909.

Application filed September 21, 1908. Serial No. 453,909.

To all whom it may concern:

Be it known that I, WILLIAM ROBINSON, a citizen of the United States, residing in Brooklyn, in the county of Kings and State 5 of New York, have invented a new and Improved Adjustable Platform for Railway-Cars, of which the following is a specification.

It is well known that where railway stations are located on the outside of curves, especially on subway or elevated railways where the station platforms are elevated, the center of the car is so far away from the station platform that it is impossible to use center doors in the cars to facilitate egress or ingress of passengers. On the other hand, if the station be located on the inside of the curve the ordinary end platforms of the car will be so far away from the station platform 20 as to render such an arrangement dangerous and impracticable.

The object of this invention is to obviate these disadvantages and to provide cars with automatically extensible platforms at 25 the center of the car and at its ends, the movable center platform arranged to extend between the car-body and the station platform on the outer side of a curved track, and the movable end platforms to extend between the car body and the station platform on the inner side of curves.

The nature of my invention will be understood from the description which follows, reference being had to the accompanying 35 drawings, which form a part of this specification, in which—

Figure 1 is a plan outline view of the lower part of a car frame showing, chiefly in dotted outline, one form of my invention as applied thereto; Fig. 2 is a side elevation of a car 40 illustrating the same; Fig. 3 is a transverse section through the line 3—3, Fig. 1; Fig. 4 is a longitudinal section through the line 4—4, Fig. 1; Fig. 5 is a cross section through the 45 line 5—5, Fig. 1; Fig. 6 is a plan view with portions of the car flooring cut away, showing another means for accomplishing the results specified; Fig. 7 is a cross section through the line 6—6 Fig. 6; Fig. 8 shows 50 means for adjusting both the center and the end movable platforms by the swiveling movement of one of the car trucks; Fig. 9 is a plan showing means for adjusting the movable end platforms independently, and Fig. 55 10 shows a detail of construction.

Referring to Figs. 1, 2, 3, 4, and 5: 10 rep-

resents a car body provided with side doors 11 at its center. The center pony truck 12 is located at the center of the car and is arranged to move freely in a straight line 60 across the same between the transverse guides 13 which are rigidly secured to the car frame. The brackets 14, also secured to the car frame, may also be used to prevent the vertical tipping or rocking of the truck frame 65 12. The rollers 15 secured to the truck frame 12 afford an easy movement of said frame between the timbers or guides 13.

The car body 10 is provided, beneath the floor 18 with the transversely movable platform 17 which is provided at its sides with the racks 19 secured thereto, while the truck 12 is provided approximately at or near its center, with a similar rack 20. The shaft 21 is provided with the pinion 22 which meshes 70 with the gear 23, which latter meshes with the rack 20. The gear 23 is supported pivotally in the hanger 24 and is pressed into firm engagement with the rack 20 by the spring 25. The gears 26 secured to the shaft 21 mesh with the racks 19 at the sides of the movable platform 17. It is evident now that when the car enters upon a curved track the truck 12 travels toward the outside of the curve, causing the rack 20 to rotate the gear 23, which in turn reverses the shaft 21 with its gears 22, 26. The gears 26 75 engaging the racks 19 cause the movable platform 17 to move in the same direction as the truck 12, all as illustrated in Figs. 3 80 and 4. In Fig. 3 the truck 12 is shown as having traveled toward the left, that is, toward the outside of the curve, relatively to the center of the car body, thus forcing the platform 17 outwardly in the same direction, as shown. It will be noted that the end of the platform 17 fills up the space between the side of the car body and the station platform 27. When a straight track is 85 reached the truck 12 returns to the center of the car, thus withdrawing the platform 17 to its normal position under the car. When the track curves in the opposite direction however, the platform 17 is thrust out on the opposite side of the car. The difference 90 in the relative distances traveled by the truck 12 and the platform 17 is determined by the relative difference in the number of teeth in the gears involved in the operation.

The shaft 21, as illustrated, is extended 110 and at its ends is provided with gears 28 which mesh with pinions 29 on the counter-

- 2
- shafts 30 thus imparting a rotation to said countershafts the reverse of that of the main shaft 21. The countershafts 30 are provided with gears 31, which mesh with racks 32 on the movable end platforms 33. . .
- From the foregoing it will be understood that the lateral movement of the center truck 12 relatively to the car body 10 forces the movable center platform 17 outwardly 10 toward the station platform 27 on the outside of the curve, and the movable end platforms 33 in the opposite direction, toward the station platform 34, on the inside of the curve. (Figs. 6 and 9).
- As illustrated in Figs. 6, 7 and 9 the center truck 12 is omitted and the movement of the adjustable platforms is secured by the swiveling movement of the usual car trucks.
- In Figs. 6 and 7 the bell crank lever 35 is pivotally connected to the car body at 36 and has its long arm engaging the movable platform 17 adjustably at 37, while its short end supports the floating lever 38 at 39. The bell crank levers 40 are pivoted to the car body at 41, and from their short ends respectively extend the connecting rods 42, 43, which engage pivotally the short end of the bell crank lever 35 and the center of the floating lever 38. The rod 44 engages pivotally one end of the floating lever 38 and one side of the truck 45 at b, while the rod 46 engages the opposite end of the floating lever 38 and the opposite side of the other car truck 47, as shown at a.
- It will be seen that when the car enters upon a curve the turning of the truck 45 on its center, as shown in Fig. 6, causes the rod 44 to pull on the end of the floating lever 38, while the rod 46 pushes the opposite end of the same lever in the same direction. Thus the floating lever 38 is moved bodily, in this case, toward the center of the car. Thus this movement of the floating lever, acting upon the rods 42 and 43 causes the bell crank levers 40 to thrust the adjustable end platforms 33 out on the inside of the curve, while the central platform 17 is extended out in the opposite direction on the opposite side of the car and of the curve.
- It will be understood that when the car enters upon a piece of track curving in the reverse direction all of the described adjustable platforms will be reversed in their direction of travel relatively to the car body.
- In Fig. 8 the described movements of the center and end adjustable platforms are shown as secured by the swiveling movement of one of the ordinary car trucks. In this case the T levers are pivoted as shown at 52 to the car body. The center lever 53 has one end of its cross head c connected pivotally by the rod 54 to one side of the truck 47 as shown at 55, and the same end of said cross head connected by the rod 61 to one end of the cross head d of the T lever 57. The opposite end of said cross head c of the lever 53 is connected by the rod 58 to the opposite side of the truck 47 at 60, and by the rod 59 to the opposite end of said cross head d of the lever 57. The cross head of the lever 53 is also connected by the crossing rods 63, 64, to the cross head e of the T lever 62. The lever 53 is connected adjustably to the center adjustable platform 17, and the levers 57 and 62 are likewise adjustably connected to the end adjustable platforms 33, all as illustrated.
- Fig. 9 shows simplified means for moving the adjustable end platforms. The lever 48, made preferably with an open center to get 80 around the swiveling mechanism of the truck, is pivoted to the car body at 49. One end of this lever is connected adjustably to the inner end of the truck at 50 and the outer end of said lever is similarly connected to the 25 movable end platform 33 as shown at 51. Thus when the car enters upon a curve said end platforms are extended outwardly toward the station platform on the inner side of the curve, as heretofore described.
- In Fig. 10 means are shown for preventing undue wear in the slots of the levers 48, 53, and others. The slots g in the ends of said levers are enlarged and provided with sliding blocks f through which extend the bolts h 95 connected to the movable platforms or trucks. Thus a large frictional surface is provided between said sliding block and the slot sides, and the coupling bolt h has a bearing all around its periphery, thus reducing 100 wear to a minimum.
- The method described in connection with Fig. 8 for accomplishing the results specified is simple and comparatively inexpensive and available when there are not too many 105 obstructions connected to the framing under the car. In most of the electric trains however there are serious obstructions under the cars, it is thought therefore that it will prove preferable to utilize the center truck 12 to 11 operate and control the center movable platform 17 alone, and the means shown in Fig. 9 to operate the movable end platforms 33. This would leave room between the center and the end trucks for the installation of such electrical or other equipment as might be required.
- It will be noted that where there is a station platform only on the outer side of the curve the movable end platforms 33 may be omitted, the adjustable platform 17 meeting the requirements. Nevertheless this invention makes a platform on each side of the car on a curve available, and in this case passengers may be discharged from center doors at both sides of the car simultaneously, and if desired, admitted from both platforms at both ends of the car at the same time. This will be clear from an inspection of Fig. 9.
- Having thus described my invention what 1

I claim as new and desire to secure by Letters Patent, is:

1. In a railway car, an adjustable platform arranged to move laterally relatively to the car body, and means for causing said car, on changing the direction of its line of travel, to automatically impart lateral motion to said platform.
2. In combination with a railway car, an adjustable platform supported thereby, and means connected to said platform and under control of said car, for causing said platform to move laterally relatively to the car body when said car changes the direction of its line of travel.
3. In combination with a railway car, an adjustable platform, and means under control of said car, for moving the same laterally relatively to the car body, the entrance of said car upon a curved track causing said platform to automatically extend outwardly beyond the side lines of the car.
4. In a railway car, an adjustable platform located between the ends of the car, means for moving the same laterally relatively to the car body, and means actuated by said car on entering a curve, to extend said platform outwardly toward a station platform when located on the outside of said curve.
5. In combination with a railway car, a laterally adjustable platform located at or near the center thereof, means connected with said platform and under control of said car, for actuating said platform, the approach of said car to a station platform located on the outside of a curve operating to extend said adjustable platform toward said station platform, and the entrance of said car upon a straight track operating to restore said adjustable platform to its normal position.
6. In a railway car, an adjustable platform located at or near the end of the car and arranged to move laterally relatively thereto, means under control of said car for causing said adjustable platform to project outwardly from the car body when the car enters upon a curved track, and to return to its normal position when the car enters upon a straight line.
7. A railway car provided with a laterally adjustable platform located at or near the end of the car, means under control of said car for imparting lateral motion to said platform, the entrance of said car upon a curved track operating to cause said platform to project toward the inner side of said curve, and its entrance upon a straight track operating to restore said platform to its normal position.
8. In a railway car, a plurality of adjustable platforms arranged for lateral move-

ment relatively to the car body, means under control of said car for causing said platforms to project from opposite sides of said car when the latter enters upon a curved track, and to return to their normal position when said car enters upon a straight line.

9. In a railway car, a laterally movable platform located at the center of the car, laterally movable platforms located at or near the ends thereof, means under control of said car for causing said central platform to project outwardly from one side of said car, and the end platforms to project from the opposite side of the car, when the latter enters upon a curved track, the entrance of said car upon a straight track causing said platforms to return to their normal position.

10. In a railway car, a transversely adjustable platform, and means for extending the same outwardly beyond the side lines of the car and restoring said platform to its normal position.

11. In a railway car an adjustable platform and means for automatically moving the same transversely relatively to the car body on the entrance of said car upon a curved track.

12. In combination, a railway car, an adjustable platform, a stationary platform located on a curved track, and means for causing said adjustable platform to automatically reduce the distance between said car and said stationary platform when said car approaches the latter.

13. In a railway car provided with trucks, the combination therewith of transversely adjustable platforms, and means connecting said platforms to said trucks, whereby the movement of the latter from their normal position relatively to the car body will cause a transverse extension of said adjustable platforms, the return of said trucks to their normal position causing said platforms to return to their normal position.

14. In a railway car, a transversely movable platform located at or near the center of the car, in combination with a transversely movable truck and suitable connections between said truck and said movable platform, whereby the transverse movement of said truck will cause a similar transverse movement of said movable platform.

15. In a railway car, a transversely adjustable platform a rack and gearing connected thereto, and means for actuating said gearing to impart transverse motion to said platform relatively to the car body.

WILLIAM ROBINSON.
